CANDLE

Betty Jane Kranz, Youngstown, Ohio

Application September 24, 1953, Serial No. 26,939

Term of patent 14 years

(Cl. D73—1)

To all whom it may concern:

Be it known that I, Betty Jane Kranz, a citizen of the United States, residing at Youngstown, in the county of Mahoning and State of Ohio, have invented a new, original, and ornamental Design for a Candle, of which the following is a specification, reference being had to the accompanying drawing, forming a part thereof.

The figure on the drawing is a perspective view of a candle showing my new design.

The opposite side of the candle is a substantial duplicate of the side illustrated.

I claim:

The ornamental design for a candle, as shown and described.
